UNITED STATES PATENT OFFICE.

FREDERICK WATSON BACH, OF NEW BOND STREET, COUNTY OF MIDDLESEX, ENGLAND.

DESIGN FOR A LAMP-SHADE.

SPECIFICATION forming part of Design No. 16,903, dated September 21, 1886.

Application filed August 12, 1886. Serial No. 210,743. Term of patent 3½ years.

To all whom it may concern:

Be it known that I, FREDERICK WATSON BACH, a subject of the Queen of England, residing at New Bond Street, Middlesex county, England, have invented or produced a new and original Design for Hollow Lamp Globes or Shades, of which the following is a full, clear, and exact specification.

The design is illustrated in the accompanying drawings, in which Figure 1 is a side elevation of a globe or shade for lamps made according to my design, and Fig. 2 a top plan view of the same.

In the drawings, the letter *b* indicates the plain ring or band, having an annular lower edge, *c*, arranged in a horizontal plane, or straight. The ring or band, at its upper por-

tion, *d*, is surmounted by petals *a*, constituting a hollow body or shell approximately globular and having the external configuration of a rose.

Having thus described my invention, what I claim is—

The design for a hollow lamp globe or shade, consisting of the ring *b*, having an annular lower edge, *c*, arranged in a horizontal plane, and surmounted at its upper portion, *d*, by the hollow shell, approximately globular, and having petals *a*, of the external configuration of a rose, substantially as shown and described.

FREDERICK WATSON BACH.
